METHOD AND APPARATUS FOR
STRIPPING INGOTS

George A. Dornin, Baltimore, Md.

Application July 24, 1934, Serial No. 736,625
Renewed April 2, 1937

25 Claims. (Cl. 22—95)

This application is in part a continuation of my co-pending application Ser. No. 713,667 filed March 2, 1934, for method and apparatus for stripping ingots, and in part a further development in 5 apparatus of the type therein disclosed. As set forth therein, I have discovered that improved results in stripping ingots are obtained by lowering a big-end-up ingot mold along guideways afforded by a guideway structure in alignment with 10 an obstruction which telescopes with an opening in the bottom of the mold to strip the ingot upon further lowering of the mold. The essential feature of the improved practice disclosed in said co-pending application above identified is the 15 guiding of the big-end-up ingot mold as it is moved downwardly in stripping the ingot; and the apparatus disclosed for practicing the improved procedure includes a guideway structure having guides or channels for engaging the mold 20 and prevent tipping or skewing of the latter either of itself or by the raising and lowering mechanism.

The present application relates more particularly to a method of stripping ingots and to the 25 mold manipulating mechanism whereby the mold is raised and lowered relative to the abutment to strip the ingot. I have shown in the present application two forms of such mechanism, one being the form disclosed in said co-pending application and the other being a further development 30 of such mechanism which eliminates the guideway structure as a separate and distinct structure, the same being in accordance with this embodiment of my invention built into the mold manipulating mechanism. My broader claims 35 are, therefore, directed to mold manipulating mechanism irrespective of whether the same cooperates with a guideway structure or is capable of functioning without the provision of a separate and distinct guideway structure; while other claims are directed to the further development of my invention according to which the guideway structure is built into the mold manipulating mechanism.

45 In the drawings which illustrate my invention, Fig. 1 is a view in side elevation of mold manipulating mechanism cooperating with a guideway structure, this mechanism being adapted to engage both the mold and the guideway structure 50 simultaneously to effect vertical movement therebetween;

Fig. 2 is a vertical sectional view on the line II—II of Fig. 1;

Fig. 3 is a perspective view of a guide member 55 or arm of the mold manipulating mechanism;

Fig. 4 is a perspective view of a mold-engaging member which is vertically movable along guideways provided by the guide members or arm;

Fig. 5 is a view in side elevation of mold manipulating mechanism embodying as part there-

of a guideway structure for guiding a mold during stripping, this mechanism being adapted to directly cooperate with a mold stool or other support;

Fig. 6 is a face view in elevation of the mechanism shown in Fig. 5; and

Fig. 7 is a sectional view on the line VII—VII of Fig. 6.

The guideway structure shown in Figs. 1 and 10 2 are illustrative of how such a structure may be built to follow out the principles of my invention. As is shown, vertical guideways extend upwardly from a base plate for guiding the mold and restraining the same for tilting out of proper alignment with the stripping pin during lowering 15 of the mold to strip the ingot. The base plate or stool 9 mounts a plurality of segments 10 which are pivoted thereto by pins 11 (see Fig. 2). Pins 12 limit swinging of the segments 10 about the pivot 11 in opposite directions. One end of the 20 segment carries a block 13 and the other end carries a stripper pin 14. In accordance with this embodiment of my invention, vertical guideways are provided which cooperate with lugs 15a and 15b on the big-end-up ingot mold 16. A suitable 25 guideway structure is provided by parallel vertical elements leaving between the same vertical channels for cooperating with the lugs 15, 15a, and 15b on the mold 16. In the embodiment shown, these vertical elements are the guide posts 18 and 19 30 whose opposed faces engage the lateral faces of the lugs 15, 15a, and 15b, while the inturned faces of the guide posts 18 and 19 engage guide surfaces on the mold itself.

In order to provide a strong and rigid structure, a longitudinal brace 20 connects the series 35 of guide posts 18 and 19, and transverse braces 21 connect the longitudinal braces 20. The structure may be further braced by corner plates welded in place in a manner which will be clearly 40 understood without illustration. The longitudinal braces are adapted to constitute guides or tracks for the lower portions of the guide members or arms of the mold manipulating mechanism, as will be better understood after a full description 45 of the latter mechanism.

Generally, the guideway structure should be 50 wheel-mounted so that when the ingots have been pushed up in the ingot molds, the same may be transported in the guideway structure to some other part of the plant such as the soaking pit. In order to simplify illustration, no wheels have been shown supporting the mold stools or base plates which carry the molds; but it will be understood that usually these supports will be wheel-mounted, the structures being formed as an integral part of a car structure if so desired.

In its broadest aspect my invention is not concerned with the pouring of the ingots, as a guideway structure with cooperating abutment 55

or abutments may be used in cooperative relation with suitable mold manipulating mechanism to perform the necessary stripping operation on big-end-up ingots which have been poured according to the customary practice. It may, however, be of advantage to strip the ingots without the necessity for transporting the molds to the guideway structure and inserting them therein.

With the construction illustrated in Figs. 1 and 2 a big-end-up ingot mold may be positioned in the guideway structure with its bottom end resting on the block 13. With the usual refractory plug 23 inserted in the customary opening 24 in the bottom of the mold, the ingot is poured and allowed to cool sufficiently to give the ingot the necessary skin strength for stripping. The mold manipulating mechanism is then engaged with the mold flange to raise the mold sufficiently to clear the stripping pin 14. The segment 10 is then swung to bring the pin 14 into alignment with the opening 24 when the mold 16 may be lowered to cause the pin 14 to enter the opening 24. Generally, this will effect the stripping of the ingots without the necessity for the application of any additional weight beyond the mass of the mold 16 itself. In a few instances, however, the ingot may stick in the mold, and in such case the mold manipulating mechanism may be operated, as will be apparent from the ensuing description, to force the mold downwardly and complete the stripping of the ingot 25.

Mold manipulating mechanism adapted to operate with a guideway structure is shown in end elevation in Fig. 1 and in greater detail in Figs. 2, 3, and 4. This mechanism includes a top beam or cross beam 30 constituting a cross head slide for the guide members or arms 32. The top beam 30 may be made from simple rolled shapes and plates, or may be made as one integral casting. Its elements, as shown in Fig. 1, include top and side plates 33 and 34. The side plates 34 terminate in inturned flanges 35 which complete the slides for the cross heads 37. As these cross heads 37 suspend the guide members or arms 32, the cross heads slide inwardly and outwardly with the guide members or arms when the latter are to be engaged with the guideway structure and/or a mold.

A transverse web 38 reinforces the cross beam 30 at its central portion. Trunnions 39 extend laterally from the top beam so as to be readily engaged by the hooks of a crane. If desired, there may be provided in addition a lifting eye 40 on top of the beam, as shown in Fig. 2.

The guide members or arms 32 are constructed with two vertical beams 42 connected at the top by a transverse web 43 and connected at the bottom by a transverse engaging member or toe 44 for engaging under the guide or track 20. The beams 42 are cut out above the engaging member or toe 44 to provide seats or recesses 46 for receiving the guide or track 20. Below this seat there is the toe 44, and above this seat or recess there is a heel 47 on each beam 42 which may rest on top of the guide or track, herein the longitudinal brace 20.

The guide members or arms 32 provide guides 48 which in the embodiment shown extend inwardly from the beams 42. Along the opposed guides thus provided, the mold engaging member 50 slides vertically. A screw 51 for raising and lowering the member 50 is threaded through a nut 52 which is rotatably mounted on a sliding support 54 on top of the cross beam 30. The periphery of the nut 52 is formed as a worm wheel

meshing with the threads on a worm 55. The nut 52 is rotatably mounted between anti-friction bearings 56 carried by upper and lower housings 57 and 58. These housings are secured to the support 54 which is slidable on rails 59 and 60 as illustrated in Fig. 1. The flanges of the support 54 are inturned, as indicated at 62, to prevent lifting of the slidable support when the nut 52 is rotated to force the screw 51 and mold engaging member 50 downwardly. The guide member or arm, mold engaging member, screw and nut, and the mechanism for rotating the nut will be duplicated on the other side of the cross beam, and the two worms 55 may be driven individually, each by its own motor 63; or a single motor may be connected by a cross shaft slidably connected as by a spline to the second set of driving gear 64 for rotating the second worm 55.

The manner in which a mold may be raised and lowered in a guideway structure either to lift or to lower the same is now clearly apparent. The motors 63 when driven in one direction operate through the screws 51 to pull the toes 66 of the mold engaging members 50 upwardly beneath the flange 67 adjacent the top of the ingot mold 16. When the motors 63 are driven in the opposite direction the mold engaging members 50 are pushed downwardly causing the heels 68 which overlie the flanges 67 to force the mold 16 downwardly. The heel 68 extends inwardly a substantial distance beyond the toe 66 making it somewhat easier to seat the mold engaging members 50 on the mold, as will be later explained more in detail.

The guide members or arms 32 in engaging a guideway structure and/or a mold are simultaneously moved towards each other; and in freeing the guide members or arms the same are simultaneously separated from each other, the cross heads 37 sliding inwardly or outwardly in the slides provided in the top beam 30. To effect such separation or inward movement of the guide members 32 I rotatably mount a screw-threaded cross shaft 70 in a bearing provided by a bracket 71. Collars 72, one to either side of the bracket 71, prevent transverse movement of the screw 70. Nuts 73 carried by the guide members 32 cooperate with the screw 70 so that when the latter is rotated the guide members 32 are simultaneously moved inwardly or simultaneously moved outwardly in accordance with direction of rotation of the shaft 70, one nut being a right-hand nut and the other nut being a left-hand nut. A motor 75 mounted on the side of the top beam 30 is connected by suitable gearing, for instance the worm gearing shown, fixed to the screw 70 to rotate the same in either of opposite directions.

A number of advantages flow from the construction described. The heel 68 extends inwardly far enough so that the mold manipulating mechanism may be lowered over a guideway structure until the heels 68 engage the tops of the flanges 67 of the mold. After the operator has become skilled in the operation of the mechanism, he can preliminarily move the screws 51 to proper position to cause the recess 46 to register with the guide or track 20. The screw 70 may then be rotated to bring the guide members 32 inwardly and engage the seats or recesses 46 with the guides or tracks 20. At the same time, the toes 66 engage under the flanges 67 of the mold. The mold manipulating mechanism is thus connected both to the mold and to the guideway structure; and the mold may be posi-

tively moved vertically either upwardly or downwardly as above referred to.

A further important advantage of the construction shown is that having once engaged the guides or tracks 20 in the seats or recesses 46, the mold manipulating mechanism may be moved along the guideway structure to engage each of a series of molds successively and strip an entire car load in a short space of time. Since the operator is called upon to position the manipulating mechanism with respect to the longitudinal guide or track 20 and the flanges of the molds but once for each car, it is obvious that the operation of stripping is considerably simplified.

The construction shown is lighter than would be possible with ordinary types of stripping cranes, and is considerably less costly; because during stripping the weight of the mold manipulating mechanism and of the mold itself, including the ingot, are borne by the longitudinal guides or tracks 20 through contact between the heel portion 47 and the tops of the guides or rails. If the mold sticks, the screws 51 come into play to positively force the mold downwardly; and if necessary the transverse engaging members or heels 44 can be drawn up against the bottoms of the tracks 40, herein the braces of the guideway structure.

As a further development of mechanism for manipulating molds in stripping, I provide mechanism adapted to raise and lower the mold relative to a stripping pin, this mechanism having as a part thereof guideways for restraining the mold from tilting during this operation. As illustrated in Figs. 5, 6, and 7, this form of mold manipulating mechanism cooperates directly with a mold stool 80, or other suitable support for a mold. As is apparent from Figs. 5 and 6, the greater part of this form of mold manipulating mechanism is identical with the form illustrated in Figs. 1, 2, 3, and 4. The top beam 30 carries the slide supports 54 on which are mounted the motors 63 driving through the gearing 64 the worm wheels 52 whose function is to bring about raising and lowering of the mold engaging members 50. In this embodiment, the motor 75 is shown mounted on a bracket 82 and drives through reduction gearing 83 the cross shaft 76, thus effecting simultaneous inward movement of the supports 54 and cross heads 37 or simultaneous outward movement thereof should the motors be reversed.

Guide members or arms 85 extend downwardly from the cross heads 37. These guide members or arms are constructed with two vertical beams 86 connected at the top by a transverse web 87 and connected at the bottom by a transverse engaging member 88 for interlocking with a track, a rail, or the edge of a support. The beams 86 are cut out above the engaging member 88 to provide seats or recesses 89 for receiving the track, rail or the like. The top of this seat or recess provides a heel portion 90 permitting each beam 86 to rest on top of the track or the edge of the support. The transverse engaging member 88 constitutes a toe for hooking under and interengaging with the longitudinal track or the like.

The portions of the beams 86 which face each other are projected toward each other to provide opposed guides 92 guiding the mold engaging members 50 for vertical movement as they are raised and lowered by the screws 51'. The guide members or arms 85 are, of course, consid-

erably longer than the guide members or arms 32 of the first embodiment, since they must extend substantially to the bottom of a mold; but it is not necessary that the screws 51' be any longer than in that embodiment, although it may in certain cases extend the usefulness of the mechanism to provide longer lifting screws 51' and thereby extend the travel of the mold engaging members 50.

The guide members or arms 85 are likewise constructed to provide guides 94 for the mold lugs 15, 15a and 15b. These guides 94 are on the inner faces of the guide members or arms 85 and may, as shown in Fig. 7, be bars or like rolled pieces welded to these faces. These guides correspond in function to the guide posts 18 and 19 of the guideway structure shown in Fig. 1; but it will be noted that here they are built into the mold manipulating mechanism.

In stripping a mold with this form of apparatus, the mold engaging members 50 are engaged with the flange 67 of a mold, as with the other embodiment; and the motors 63 rotated in the proper direction for raising or lowering the mold 16. With this embodiment, as with the first described embodiment, it is possible to raise or lower the mold and even to force the mold down along the guides 94.

The mold stool or other support 80 preferably has its edges 96 formed as tracks or rails adapted to engage in the recesses 89. This provides an interengagement between the guide members or arms 85 and the mold stool or support 80. Accordingly, if a mold should stick in stripping, the screws 51' may be operated to force a mold 16 downwardly even to the extent of pulling the arms 85 upwardly to engage the toes 88 beneath the tracks 96, thus transmitting upward thrust to the stool or support 80 and partially offset the downwardly directed force incident to the stripping operation. This makes it possible to lighten the load placed upon the supporting structure, which as above mentioned will generally be a wheel mounted structure.

The support 80 is shown in Figs. 5 and 7 as provided with devices for permitting the mold to be first poured while resting on the support 80 and then stripped without the necessity for transporting it to another support. A slide 98 is reciprocable between abutments 99 and 100, these abutments providing supports for diagonally opposite corners of the mold 16. Ribs 101 extend upwardly from the support or stool 80 one to either side of the slide 98 for guiding it in its reciprocations. These ribs 101 provide further support for the mold 16. A block 103 on one end of the slide 98 cooperates with the bottom of the mold 16 during pouring; and for the stripping operation the slide is moved to the other end of its travel to bring the stripping pin 104 into registry with the opening in the bottom of the mold. The operation of this second embodiment of my invention will be obvious in view of the description of the operation of the first embodiment.

In certain instances, it may be found advantageous to simplify the construction of the mold support, eliminating the guideway structure from this support and building such structure into the mold manipulating mechanism itself. The mold will be not only supported but also guided by the mold manipulating mechanism so that the mold is prevented from tilting or skewing while it is being manipulated. After the stripping operation the support 80 may be wheeled away to the

soaking pit, leaving the mold manipulating mechanism behind for further stripping operations to take care of more molds as ingot pouring proceeds.

5 While I have illustrated and described certain embodiments which my invention may assume, it will be understood that my invention is not restricted to the particular constructions and arrangements shown but may be variously modified and embodied or practiced within the contemplation of the invention and under the scope of the following claims.

I claim:

1. Apparatus for stripping ingots comprising a mold stool provided with an abutment for projecting into an opening in the bottom of the ingot mold, and mold manipulating mechanism cooperating with said stool and movable relative thereto, said mechanism including structure for guiding an ingot mold in a predetermined vertical path relative to and in alignment with the abutment while the mold is telescoping therewith, and means engageable with the mold for raising and lowering the mold relative to the guiding structure and the abutment on the stool.

2. Apparatus for stripping ingots comprising a mold stool, an abutment mounted on the stool for projecting into an opening in the bottom of the ingot mold, and mold manipulating mechanism cooperating with said stool and including structure having guides for lugs on an ingot mold to maintain the mold in alignment with said abutment and means for raising and lowering the mold relative to said structure and the abutment, said structure and the stool having portions adapted to interengage to take thrust during the stripping operation.

3. Apparatus for stripping ingots comprising a mold stool having an abutment for projecting into an opening in the bottom of an ingot mold, a guideway structure, said stool and structure having cooperating portions for guiding said structure longitudinally of the stool, and means for raising and lowering the mold relative to said structure, said structure providing a guideway for maintaining an ingot mold in alignment with said abutment during lowering of the mold to strip its ingot.

4. Apparatus for stripping ingots comprising a mold stool having an abutment for projecting into an opening in the bottom of an ingot mold, and mold manipulating mechanism having arms engageable with the stool and movable relative thereto, and means for raising and lowering an ingot mold relative to said arms, the latter providing guides cooperating with the mold to maintain the mold in alignment with said abutment during lowering of the mold.

5. Apparatus for stripping ingots comprising a mold stool having an abutment for projecting into an opening in the bottom of an ingot mold, and mold manipulating mechanism having arms cooperating with a mold to guide the mold during the lowering of the mold when stripping, and means for raising and lowering the mold relative to said arms, the latter affording guides engageable by lugs on the mold to maintain the mold in alignment with said abutment during lowering of the mold.

70 6. Apparatus for stripping ingots comprising a mold stool having an abutment for projecting into an opening in the bottom of an ingot mold, and mold manipulating mechanism having guide members movable along the edges of the stool and engageable therewith to guide the guide

members along the stool, and means for raising and lowering the mold relative to said guide members, the members affording channels engageable by lugs on the mold to maintain the mold in alignment with said abutment during lowering of the mold.

7. Apparatus for stripping ingots comprising a mold stool having an abutment for projecting into an opening in the bottom of an ingot mold, and mold manipulating mechanism having guide members providing channels engageable by lugs on the mold to maintain the mold in alignment with said abutment during lowering of the mold, and means for raising and lowering the mold relative to said members.

8. Mold manipulating mechanism comprising a cross-head slide, guide members having cross-heads, said cross-heads being slideable horizontally in said slide, said guide members providing vertical guideways, mold engaging members vertically movable along the guideways provided by said guide members, and means for raising and lowering said mold engaging members relative to said guide members.

25 9. Mold manipulating mechanism comprising a cross-head slide, a pair of guide members having cross-heads, said cross-heads being slideable horizontally in said slide, means for sliding said guide members simultaneously inwardly and simultaneously outwardly, said guide members providing vertical guideways, a pair of mold engaging members vertically movable along the guideways provided by said guide members, and means for raising and lowering said mold engaging members relative to said guide members.

30 10. In apparatus for stripping ingots, the combination of a cross beam, a pair of guide members carried thereby and slideable thereon toward and from each other, said guide members providing vertical guides, mold engaging members vertically movable along the guides provided by said guide members, and power operated means movable toward and away from each other with said guide members for raising and lowering said mold engaging members.

45 11. Apparatus for stripping ingots from molds which are elongate vertically comprising an abutment adapted to project into an opening in the bottom of the ingot mold, a guideway structure for guiding the ingot mold in alignment with said abutment and preventing swaying or tilting of the mold while in operative relation to the abutment, and means associated with said structure and engageable with the mold for raising and lowering the mold along the guides provided by said guideway structure so as to telescope with said abutment.

50 12. Apparatus for stripping ingots from molds which are elongate vertically comprising an abutment adapted to project into an opening in the bottom of the ingot mold, a guideway structure affording lateral contact with the elongate mold during up and down movement thereof both for preventing tilting of the axis of the mold and for guiding the lower portion thereof in alignment with said abutment, and means maintained in fixed relation to said structure during stripping for raising and lowering the mold along the guideway provided by said structure so as to telescope with said abutment.

65 13. Mold manipulating mechanism comprising guide members having vertical guideways, mold engaging members movable vertically along said guideways, means for carrying said guide members and moving them simultaneously

70 75

- toward each other and simultaneously from each other, and means for raising and lowering the mold engaging members along said guideways relative to the guide members.
- 5 14. Mold manipulating mechanism comprising guide members, mold engaging members guided vertically by said guide members, means for carrying said guide members and moving them simultaneously toward each other and 10 simultaneously from each other, and means for raising and lowering the mold engaging members relative to the guide members, said guide members having guideways for the mold for the purpose of determining its path during raising and 15 lowering.
15. Apparatus for stripping ingots comprising an abutment adapted to project into an opening in the bottom of an ingot mold, a guideway structure cooperating with the mold during up 20 and down movement thereof for preventing sway of the upper portion of the mold and for guiding the lower portion thereof in alinement with said abutment, and mold manipulating mechanism comprising guide members, mold engaging members 25 guided vertically by said guide members, means for carrying said guide members, and means for raising and lowering the mold engaging members relative to the guide members.
16. Apparatus for stripping ingots comprising 30 a guideway structure for guiding a mold in a predetermined vertical path and preventing tilting of the mold during movement along the path, an abutment cooperating with said structure for entering the mold to prevent downward movement 35 of the contained ingot as the mold is lowered, and mold manipulating mechanism operable to move the mold in said predetermined vertical path relative to said structure, the latter providing an upwardly directed surface upon 40 which the mold manipulating mechanism may rest and cooperating with said mechanism for positioning the same relative to the mold.
17. Apparatus for stripping ingots comprising 45 a structure providing vertical channels, an ingot mold carrying guides for cooperating with said channels and having an opening in the bottom of said mold, a stripping pin, guides cooperating therewith to guide the same in a predetermined path to operative and inoperative positions, and 50 means for vertically moving the mold relative to said structure.
18. Apparatus for stripping ingots comprising 55 a guideway structure for guiding a plurality of molds in predetermined vertical paths, means cooperating with said structure for entering the molds to prevent downward movement of the contained ingot, and mold manipulating mechanism engageable both with said structure and with said molds, said structure providing guides 60 for guiding said mold manipulating mechanism for horizontal movement to permit positioning thereof in cooperative relation with a selected mold, said mechanism being operable in such relation to move the mold in said predetermined vertical path relative to said structure.
- 65 19. In apparatus for stripping big-end-up ingots from molds, a guideway structure to confine the movement of the mold to vertical move- 5 movement only while in the guideway structure, a blocking member for stopping the downward movement of the ingot at a predetermined point, means for moving the blocking member into positive coaxial relationship with the ingot, and 10 mold manipulating mechanism engageable with a mold to cause vertical movement of the mold within the guideway structure, said mechanism having rests engageable with said guideway structure for supporting said mechanism thereon. 15
20. In apparatus for stripping big-end-up ingots from molds, the combination of a guideway structure adapted to guide a mold and permit vertical movement thereof while restraining skewing or tilting of the upper portion of the 20 mold, a stripping pin cooperating with the guideway structure and alined with the path of movement of the mold bottom, and mechanism connectable simultaneously to the mold and to the guideway structure to lift, lower and force the 25 mold downwardly relative to the guideway structure and stripping pin, said structure providing a portion for positioning said mechanism and for receiving downward thrust therefrom.
21. Apparatus for stripping ingots comprising 25 a stripping pin, mold manipulating mechanism for raising and lowering a mold relative to said pin, and a guideway structure for guiding a mold in alinement with said pin, said mechanism being 30 engageable with said structure that the latter supports said mechanism in part at least.
22. In a method of stripping ingots the steps 35 consisting of pouring molten metal into a big-end-up ingot mold, sliding the mold with its contained ingot upwardly in a guideway structure, positioning an abutment beneath the mold, and sliding the mold downwardly in the guideway structure to strip the ingot from the mold by engagement of the ingot by said abutment.
23. The method of stripping big-end-up ingots 40 by engaging the mold in vertical guideways and thereby confining the mold to vertical movement along a predetermined path only, moving mold and contained ingot vertically upward along 45 the guideways, blocking the ingot against downward movement, and then effecting similarly guided vertically downward movement of mold.
24. In the method of stripping big-end-up ingots the steps of restricting by a guideway structure the movement of the mold and its contained 50 ingot to vertical movement along a predetermined path, then moving the mold and its contained ingot vertically upward along said path, then positioning a blocking member under the ingot in coaxial alinement therewith, and then lowering 55 the mold guided solely by the guideway structure.
25. Apparatus for stripping ingots comprising 60 a structure providing vertical guideways for the mold to be separated from its ingot, and a movable abutment provided with guides for guiding the abutment to and from operative position beneath the mold in registry with an opening in the mold, said abutment being adapted when in operative position to enter said opening in the mold during downward movement of the mold 65 for the purpose of separating the ingot from the mold.

GEORGE A. DORRIN.
